WITNESS:

INVENTOR
BY *Victor J. Evans*

ATTORNEY

UNITED STATES PATENT OFFICE.

HAROLD M. HURLBERT, OF GLENDALE, CALIFORNIA.

HORN.

Application filed May 13, 1927. Serial No. 191,162.

This invention relates to improvements in amplifying horns and sound conveyors, and its general object is to provide a radio loud speaker that is capable of reproducing sound in an extremely clear, accurate and exact manner due to the fact that the construction of the present invention is so formed to absorb all vibration before they reach the outlet opening thereof.

5 A further object of the invention is to provide a horn of the character set forth, that is extremely simple in construction, inexpensive to manufacture and the sound passage thereof is of sufficient length to co-15 operate with vibrating absorbing material so that all vibration caused by operation and the like will be completely absorbed or removed.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the sev-30 eral views, and in which:—

Figure 1 is a sectional view taken approximately on line 1—1 of Figure 2.

Figure 2 is a sectional view taken approximately on line 2—2 of Figure 1.

35 Referring to the drawings in detail the reference numeral 1 indicates an elongated container formed from metal or other like material and has arranged preferably in one corner thereof as shown in the drawings, a 40 chamber 2 to accommodate the reproducing unit 3. The chamber 2 is provided with a hinged door 4 having a knob 5 thereon whereby the unit may be removed as will be apparent. The upper wall of the chamber 45 is formed with an opening which is reinforced by an eyelet 6 through which is adapted to pass the cords leading to a radio set or the like.

Arranged in the container is a passage 50 formed by a circular wall which forms the sound chamber and the wall tapers gradually from its small end 7 which is disposed within the chamber 2 to receive the unit, and is thence extended downwardly and curved 55 upon itself as at 8 to provide an upturned portion 9 disposed in parallelism with the

portion first mentioned, is again extended downwardly to provide a relatively enlarged portion 10 which is likewise disposed in parallelism with the portion 9 and the first 60 mentioned portion. The wall from the portion 10 is again curved upwardly upon itself and terminates in an enlarged outlet end 11 which is disposed at right angles to the small end of the wall as best shown in Figure 65 2 of the drawings.

Arranged within the container and disposed between the respective portions of the wall is material 12 preferably composed of rubber or like resilient material which includes absorbing qualities so that vibrations created by the sound waves in passing through said sound chamber will be entirely absorbed before reaching the outlet end 11 as will be apparent.

75 From the above description and disclosure of the drawings, it will be obvious that I have provided a neat and compact amplifying horn that can be conveniently arranged within a cabinet or supported in any appropriate place or manner due to the flat walls of the container 1, and in view of the length of the sound chamber and the absorbing qualities of the material 12, all 80 noises caused by vibrating of the parts will 85 be absorbed before they have reached the outlet end 11, with the result, that the reception will be clear, accurate and exact.

It is thought from the foregoing description that the advantages and novel features 90 of my invention will be readily apparent.

I desire it to be understood that I may make changes in the construction and in the combination and arrangement of the several parts, provided that such changes fall 95 within the scope of the appended claims.

What I claim is:

1. An amplifying horn of the character described comprising an elongated metallic container, a unit receiving chamber formed in said container, said container having a passage disposed therein and being formed by a circular wall, said wall providing a sound chamber which includes parallel portions and a portion arranged at right angles 100 to the parallel portions, said sound chamber being connected at one end with the unit chamber and tapered gradually therefrom to its outlet end, and sound absorbing material arranged in said container and disposed 105 between the walls thereof and the wall of the sound chamber.

2. An amplifying device of the character described comprising an elongated container having a passage arranged therethrough and formed by a circular wall, said wall providing a sound chamber which includes portions arranged in parallelism and a portion disposed at right angles to the parallel portions, a unit receiving chamber disposed in said container for receiving one end of the sound chamber which is tapered from said end to its opposite end, said opposite end

providing the outlet for the chamber, said unit receiving chamber adapted to receive a unit for connection with the small end of the sound chamber, a hinged door for said unit receiving chamber, and sound absorbing material disposed between the wall of the sound chamber and the walls of the container. 15

In testimony whereof I affix my signature.

HAROLD M. HURLBERT.
